DESIGN FOR A SHOE HEEL

Herbert T. Mason, North Brookfield, Mass., assignor to Quabaug Rubber Company, North Brookfield, Mass., a corporation of Massachusetts

Application April 19, 1934, Serial No. 51,445

Term of patent 14 years

To all whom it may concern:

Be it known that I, HERBERT T. MASON, a citizen of the United States, residing at North Brookfield, in the county of Worcester, and State of Massachusetts, have invented a new, original, and ornamental Design for Shoe Heels, of which the following is a specification, reference being had to the accompanying drawing, forming part thereof.

Fig. 1 is a view in perspective of a shoe heel with plan of the tread portion thereof, showing my new design.

Fig. 2 is a cross section on the line 2—2 of Fig. 1.

Fig. 3 is a cross section on the line 3—3 of Fig. 1.

I claim:

The ornamental design for a shoe heel as shown.

HERBERT T. MASON.
